Primary Examiner — Jeffrey D Asch*Assistant Examiner* — Caitlin A Laverty(74) *Attorney, Agent, or Firm* — Rumit Ranjit Kanakia(57) **CLAIM**

I claim the ornamental design for a soap box, as shown and described.

DESCRIPTION

FIG. 1 is a Perspective view of a soap box showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof; and,

FIG. 8 is open perspective view thereof.
